United States Patent Office.

F. B. MORSE, OF NEW HAVEN, CONNECTICUT.

Letters Patent No. 65,762, dated June 11, 1867.

IMPROVED METHOD OF MANUFACTURING SHACKLES FOR CARRIAGE-THILLS.

The Schedule referred to in these Letters Patent and making part of the same.

TO ALL WHOM IT MAY CONCERN:

Be it known that I, F. B. MORSE, of New Haven, in the county of New Haven, and State of Connecticut, have invented a new improvement in Dies for Forging Carriage-Shackles; and I do hereby declare the following, when taken in connection with the accompanying drawings and the letters of reference marked thereon, to be a full, clear, and exact description of the same, and which said drawings constitute part of this specification, and represent, in—

Figure 1, a perspective view of the upper part of the first die inverted.

Figure 2, a perspective view of the under part of the die.

Figure 3, a perspective view of the blank in the form in which it leaves the first die, full size.

Figure 4, a perspective view of the under part of the second die.

Figure 5, a perspective view of the upper part of the second die inverted.

Figure 6, a top view of the shackle after the first operation in the second die, full size.

Figure 7, the same after the second operation.

Figure 8, the same after the third and last operation.

Figure 9, the shackle complete.

Heretofore carriage-shackles have been formed by welding the ears to the clip. This has required the riveting of the two parts together, or otherwise securing them, preparatory to welding. The process of welding, and that preparatory thereto, costs no inconsiderable amount of time, and this taken with the fact that the two parts must be first forged separately, and that after being welded the ears must be turned up. This turning up requires a peculiar operation in order to form a square back-shackle.

By my invention the difficulties attending the forming of a square back-shackle, and much of the time and labor required in forging the old shackle, are saved, and a shackle produced superior to the old, in that it is formed from solid metal without welding or bending; and in order to the better understanding of my invention, as well as to enable others to construct the same, I will proceed to a description as illustrated in the accompanying drawings.

A is the first or breaking-down die. The upper or opposite part, B, being of the same form, simply breaks down the metal each side of the head C, (see fig. 3.) Next the blank is placed in the part D, beneath the part E of the die, and there brought to the proper length. Thence it is placed in the die F, into which the part G of the upper part falls and strikes the head C of the shank H into the form denoted in fig. 3. Thence the blank is removed and the end I rounded between the dies J and K, which finishes the operation by the first dies leaving the blank, as seen in fig. 3. Thence the blank is taken to the second die, seen in fig. 4, and the end I of the blank inserted into the hole a in the first part of the said die. In the central part of this portion of the die a convex block, L, is set, and in the upper part a corresponding convex block, M, and the upper part formed so as to allow free passage of the die down over the shank H. Thus the die strikes upon the head C and forms the head, as seen in fig. 6. Removed from the first part of the die, it is inserted into the second part, the end I entering the hole d, and a block, N, in the lower part, and a corresponding block, O, in the upper part of the die, strike the head into the form seen in fig. 7, thence removed and inserted in like manner into the third part of the die, entering the hole f. The block P in the lower part, and block R in the upper part of this die, are nearly square, so as to strike the head into the form seen in fig. 8. This operation leaves a web or fin, S, across the head at the meeting of the dies, as seen in fig. 8. Thence the blank is taken to the milling machine or trimming dies, where the said web or fin is removed and the shackle finished, as seen in fig. 9. Thus I have formed a square back-shackle from solid metal at a single heat, without welds or bending, and therefore have produced a shackle cheaper, in that it is produced at not exceeding one-half the expense of the common shackle, and better, in that it is produced from solid metal.

I do not wish to be understood as broadly claiming a shackle formed from a single piece.

Having thus fully described my manner of producing such a shackle, what I claim as new and useful, and desire to secure by Letters Patent, is—

The method herein described of forming the square-backed shackle-blank described and represented by fig. 8 of the drawings.

F. B. MORSE.
